DESIGN FOR A COAT

Adolph H. Sadiker, New York, N. Y.

Application October 30, 1939, Serial No. 87,924

Term of patent 3½ years

To all whom it may concern:

Be it known that I, Adolph H. Sadiker, a citizen of the United States of America, residing in New York city, in the Borough of Manhattan, county and State of New York, have invented a new, original, and ornamental Design for a Coat, of which the following is a specification, reference being had to the accompanying drawing, forming part thereof, wherein:

Figure 1 is a front view of a coat showing my new design.

Figure 2 is a rear view of the coat shown in Figure 1.

The design is characterized by the combination on the coat disclosed of the specific collar in association with the two buttons at each side of the top center button forming a straight line therewith across the top of the coat as shown.

I claim:

The ornamental design for a coat, substantially as shown and described.

ADOLPH H. SADIKER.
